UNITED STATES PATENT OFFICE

159,141

PACKAGE GRIP

Samuel L. Conrad, Hollywood, Calif.

Application July 1, 1949, Serial No. 3,665

Term of patent 14 years

(Cl. D17—5)

To all whom it may concern:

Be it known that I, Samuel L. Conrad, a citizen of the United States, residing at Hollywood, in the county of Los Angeles and State of California, have invented a new, original, and ornamental Design for Package Grip, of which the following is a specification, reference being had to the accompanying drawing, forming part thereof.

Fig. 1 is a perspective view of a package grip, showing my design;

Fig. 2 is a side view of the package grip;

Fig. 3 is an end view of the package grip; and

Fig. 4 is a sectional view of the same taken on line 4—4 of Fig. 3.

I claim:

The ornamental design for a package grip, as shown.

SAMUEL L. CONRAD.
